UNITED STATES PATENT OFFICE.

ELMENDORF J. HEDDEN, OF BALA, PENNSYLVANIA.

RETAINING AND REINFORCING DEVICE FOR PLASTER-BOARD AND STUCCO CONSTRUCTION.

1,169,641.

Specification of Letters Patent. Patented Jan. 25, 1916.

Application filed March 22, 1915. Serial No. 16,019.

To all whom it may concern:

Be it known that I, ELMENDORF J. HEDDEN, a citizen of the United States, residing at Bala, county of Montgomery, and State of Pennsylvania, have invented a new and useful Improvement in Retaining and Reinforcing Devices for Plaster-Board and Stucco Construction, of which the following is a full, clear, and exact description, reference being had to the accompanying drawings, which form a part of this specification.

My invention relates to the art of securing plaster boards or composition boards to studding and of applying plaster or stucco to such boards, and is more especially applicable to the construction of the outside walls of buildings, although applicable also to inside partition work.

In this construction the plaster boards are nailed in place upon the studding and then a coat of stucco is applied thereto. Defective work often arises from several causes. Thus, the material of which the plaster boards is formed is not such as to tightly grip the shank of the nail, as in wood-work, and thus the board tends to work loose and work out in the direction of extension of the nail. This defect is in a large measure overcome by the provision of specially constructed nails having large heads formed of convoluted wire integral with the nail; but such nails are expensive to manufacture and the head is easily broken from the shank, and moreover they cannot be driven into place as readily as the ordinary nail. Again, due to the failure of the workmen to properly wet the face of the boards, the plaster or stucco often fails to properly adhere thereto. Again, there is nothing except the closest supervision, which is usually impracticable, to prevent the workmen from applying too thin a coat of stucco or from applying a coat of irregular thickness.

It is the object of my invention to overcome all these sources of defective, dishonest or slip-shod work, to which end I have provided a wire retaining and reinforcing device designed to be used in connection with an ordinary lath nail, and constructed, preferably, as shown in the drawings in which—

Figure 1 is a perspective view of the retaining or reinforcing device. Fig. 2 is a plan view of same in use. Fig. 3 is a sec-

tion through a wall showing the device in 55 elevation.

The drawings show the application of the invention to a typical plaster board and stucco construction, the frame-work or studding being shown at *a*, the boards at *b* and the coat of stucco at *c*. For the purpose of securing the boards to the studding, I employ an ordinary lath nail *d*. Before driving a nail, there is slipped on the shank thereof a wire retainer and reinforcer comprising a single length of wire. The central portion of the wire is bent into a loop *e*, the central portion of the loop being somewhat widened to afford a passage for the shank of the nail. Beyond the loop, on each side 60 thereof, the wire is bent upon itself to form another and open-ended loop *f*, of about half the length of the first loop, and is thence bent outward, thence at an angle to the plane of loops *e* and *f*, and thence outward 65 and back upon itself to form an offset end loop *g*, which extends in a plane parallel to, but different from, the plane in which loops 70 *e* and *f* extend.

This retainer and reinforcer has several 75 important advantages. It permits the use of an ordinary nail. It is inexpensive to manufacture. It prevents the board from working away from the studding. Inasmuch as most of the usual orifices for the 80 receipt of nails are located along the margin of the board, each device applied near the margin of the board overlaps an adjacent board and thereby affords additional means 85 for securing the latter board in place, besides maintaining flush the faces of adjacent boards. It affords reinforcement for the stucco, so that the latter will be maintained in place notwithstanding the carelessness or ignorance of the workman. The 90 outer loops, spaced as they are from the face of the boards, absolutely requires the application of a coat of stucco or plaster of sufficient thickness to entirely cover and conceal the loops, thereby insuring, without special 95 supervision, the application of a coat of the thickness required by the specifications.

It is obvious that the precise contour of the reinforcing and retaining device, although it possesses advantages, need not be 100 strictly adhered to, so long as the essential features thereof are retained.

Having now fully described my invention,

what I claim and desire to protect by Letters Patent is—

1. A retaining and reinforcing device for plastic board construction comprising a length of wire having end portions in the same plane and spaced apart and a connecting portion between the end portions and located in a different plane therefrom, the central part of said connecting portion being shaped to form a loop located substantially midway between the end portions and which is adapted to receive the shank of a nail and to be confined by the nail head against the face of the board.
2. A retaining and reinforcing device for plaster board construction comprising a length of wire having end loops in the same plane and spaced apart, and a connecting portion between the end loops, said connecting portion being shaped to form a central loop located midway between the end loops in a plane different from that in which the end loops extend and which is adapted to receive the shank of a nail and to be confined by the nail head against the face of the board.
3. A retaining and reinforcing device for plaster board construction comprising a length of wire the central portion of which is formed into an elongated loop whose mouth is substantially closed and which between its opposite ends is somewhat spread apart to receive the nail shank, the wire from both sides of the mouth of the loop extending outward and thence formed with offset portions laterally distant from the central loop and extending in a plane different from, and parallel to, that in which the central loop extends.
4. A retaining and reinforcing device for plaster board construction comprising a length of wire the central portion of which is formed into an elongated loop to receive the shank of a nail, the wire beyond each end of said loop being bent upon itself to

form another and shorter loop and thence bent outward and back upon itself to form an end loop, the central loop and end loops being in different planes.

5. A retaining and reinforcing device for plaster board construction comprising a length of wire the central portion of which is formed into a loop to receive the shank of a nail, the wire beyond each end of said central loop being bent outward, thence angularly, and thence outward and back upon itself to form an end loop, the central loop and end loops being in different planes.

6. A retaining and reinforcing device for plaster board construction comprising a length of wire the central portion of which is formed into an elongated loop which between its ends is spaced apart to afford a guide for the shank of a nail, the wire beyond each end of said central loop being bent upon itself to form a shorter intermediate loop, and thence bent successively outward, angularly, and outward and backward, the last named outward and backward bend forming an end loop and extending in a plane different from, but parallel to, the plane in which the central loop extends.

7. A retaining and reinforcing device for plaster board construction comprising a length of wire comprising a central loop adapted to receive the shank of a nail and to be confined by the nail against the face of the board, connecting loops located on opposite sides of, adjacent to, and in substantially the same plane as, the central loop, and other loops beyond the last named loops and extending in a plane different from that in which the central loop extends.

In testimony of which invention, I have hereunto set my hand, at Philadelphia, on this 18th day of March, 1915.

ELMENDORF J. HEDDEN.
